(57) **CLAIM**

The ornamental design for a light for digital camera, as shown and described.

DESCRIPTION

FIG. 1 is a top front perspective view of a light for digital camera;

FIG. 2 is a front view thereof;

FIG. 3 is a rear view thereof;

FIG. 4 is a left-side view of the light for digital camera of FIG. 1;

FIG. 5 is a right-side view thereof;

FIG. 6 is a top view thereof; and

FIG. 7 is a bottom view thereof;

FIG. 8 is another front view thereof combined with a digital camera;

FIG. 9 is another front view thereof, in which a lighting portion is rotated by 90 degree with respect to a digital camera; and,

FIG. 10 is another front view perspective view thereof, in which a digital camera and a lighting portion are inclined obliquely with respect to a grip.

The broken line showing is for environment purposes only and forms no part of the claimed design.
